(57) **CLAIM**

The ornamental design for the hair brush as shown and described.

DESCRIPTION

FIG. 1 is a perspective view of a hair brush, showing my new design;

FIG. 2 is a top plan view thereof;

FIG. 3 is a bottom plan thereof;

FIG. 4 is a front elevation view thereof;

FIG. 5 is a rear elevation view thereof;

FIG. 6 is a right side elevation view thereof; and,

FIG. 7 is a left side elevation view thereof.

The dashed broken lines in the drawings illustrate portions of the hair brush that form no part of the claimed design.
